ATTACHMENT FOR HAIR CLIPPERS

Filed Dec. 2, 1932

Fig. 1.

UNITED STATES PATENT OFFICE

1,928,000

ATTACHMENT FOR HAIR CLIPPERS

Giorgi Adelmo, Highwood, Ill.

Application December 2, 1932. Serial No. 645,475

3 Claims. (Cl. 30—1)

My invention relates to improvements in attachment for hair clippers, and it consists in the combinations, constructions, and arrangements herein described and claimed.

5 An object of my invention is to provide an attachment for electric hair clippers which will enable the operator, whether he be a skilled barber or an inexperienced novice, to cut the hair evenly and to easily and gradually vary the depth 10 of the cut, whereby the hair may be left short or relatively long as may be desired.

A further object is to provide an attachment for electric hair clippers which will not become clogged or inoperable by the cut hair.

15 A further object is to provide an attachment for electric hair clippers which is simple in construction, and which may be quickly and easily connected with or detached from the clipper.

Other objects and advantages will appear in 20 the following specification, and the novel features of the invention will be particularly pointed out in the appended claims.

25 My invention is illustrated in the accompanying drawing, forming part of this application, in which

Figure 1 is a side elevation of an electric hair clipper showing my invention connected therewith;

Figure 2 is an oblique top view of the end of 30 the clipper and my attachment connected therewith;

Figure 3 is an enlarged detail sectional view 35 taken substantially along the line 3—3 of Figure 2, the comb being shown in dotted lines;

Figure 4 is a detail sectional view taken along the line 4—4 of Figure 3;

Figure 5 is a side elevational view of the end 40 of a clipper showing an alternative form of my invention connected therewith, and

Figure 6 is a top plan view of the attachment shown in Figure 5, the clipper being shown in dotted lines.

In carrying out my invention, I make use of a 45 conventional electric hair clipper 1 which comprises a handle portion 3 and a head portion 5. The head portion is provided with a reciprocable cutting blade 7 which is actuated by an electrically operated mechanism disposed in the handle portion. Conductors 9 provide communication 50 between the mechanism and a power supply means, and a switch is provided for controlling the operation of the mechanism.

A stationary cover plate or guard 13 is 55 connected with the head portion 5 and extends over the blade 7. The blade 7 is in sliding engage-

ment with the plate 13, and both the blade and the plate are provided with teeth for shearing the hair.

The structure described above, however, forms no part of my invention, but has been recited merely for the purpose of clearly disclosing the nature of my invention and the device with which it is adapted for use.

The invention consists of a body member or comb retaining member 15, which is preferably shaped as shown in Figures 1 and 2 and may be made of any suitable material such as aluminum. The body member has been illustrated as being longer than the width of the plate member 13 and may be formed for providing a pair of spaced 60 apart projecting end portions 17 for receiving a comb 19 and the plate member 13 therebetween.

The end portions 17 may have flange portions 21 for providing recesses 23 for receiving the ends of the comb for slidably connecting the comb with the end portions. In like manner the end portions 17 may also have flange portions 25 for providing recesses 27 for receiving the lowermost corners of the plate member 13 for fixedly positioning the body member 15 with respect to the plate member 13 and also serving in part to connect the body member with the plate member.

The body member 13 is further provided with an attachment portion 29 for being pivotally connected with a resilient fastening member 31 which may be constructed of a strip of spring steel.

The attachment portion 29 may be formed integral with the body member or may be formed by connecting a U-shaped member with the body member in any suitable manner.

The fastening member 31 is formed for providing a plate engaging portion 33, a comb engaging portion 35, in engagement with the top portion 20 of the comb 19, and is provided with a looped portion 37 for pivotally connecting the fastening member 31 with the attachment portion 29 of the body member 15.

In connecting the device with the head 5 of the clipper, the lowermost corners of the plate 13 are first positioned within the recesses 27 of the end portions 17 and in engagement with the end portions, and the plate engaging portion 33 of the fastening member 31 is then snapped over the end 14 of the plate for engaging the same where by the body member may be retained in position.

It will be noted that the plate 13 is of greater width than the blade 7 so that the reciprocating

blade will not strike the end portions 17 when they are connected with the plate member 13.

Normally the comb engaging portion 35 of the fastening member 31 tends to yieldingly retain the comb in its lowermost position shown in Figures 1, 2 and 3, due to the resiliency of the fastening member 31, at which time the top portion 20 of the comb may engage the end portions 17 over which the top portion 20 of the comb may 10 extend.

Due to the fact that the teeth of the comb preferably taper from the top portion 20 to the ends, the lowermost position of the comb may be determined by the width of the recesses 23.

15 When the clipper is used with my device attached, the handle 3 of the clipper is held in the hand of the operator in a manner similar to that for holding a pencil. The comb is held substantially vertical to the surface of the head. As the 20 comb is moved from the top portion of the head downwardly, the hair extending above the blade 7 is cut off by the reciprocating teeth of the blade.

25 As the comb is moved downwardly pressure may be exerted on the handle by the operator which will result in the comb being moved upwardly with respect to the blade and the blade being moved downwardly with respect to the head, thereby increasing the depth of the cut. 30 The pressure on the handle may be gradually increased during the travel of the comb along the head until the comb is moved to its uppermost position with respect to the blade as shown in dotted line position in Figure 1, at which time 35 the hair will be cut quite short.

It will be noted that when the comb is moved upwardly with respect to end portions 17, the taper of the end teeth of the comb will result in the comb being loosely held by the end portions 40 17, thereby permitting the top portion 20 of the comb to remain in engagement with the comb engaging portion 35, and preventing binding therebetween or between the comb and the end portions 17.

45 When it is desired to detach my device from the clipper, the plate engaging portion 33 of the fastening member 31 is moved out of engagement with the end 14 of the plate.

When it is desired to substitute a different type 50 of a comb for the one in use, such as a fine comb for a coarse one, the device is detached from the clipper and the fastening member 31 pivoted about the attachment portion 29, at which time the comb engaging portion 35 will not hinder the 55 removal and replacement of the combs, so that the combs may be quickly and easily interchanged, after which the device may again be quickly connected with the clipper.

60 In Figures 5 and 6 I have shown an alternative form of my invention in which the attachment is shown as comprising a body portion 39 formed from a sheet of metal such as spring steel for providing a pair of spaced-apart side arms 41 and 65 an intermediate resilient extension 43, which terminates in a hooped end or comb-retaining portion 45.

The body portion is also formed for providing 70 an extension 47 having a flanged end portion 49 for engaging the rear edge of the plate 13'. The extension may be provided with a projecting por-

tion 51 for being gripped by the fingers of the operator.

Each of the side arms 41 has a top portion 53 and an inwardly projecting lower flange end portion 55 disposed in spaced relationship with the top portion for receiving the tapered end 57 of the plate 13' therebetween. The flange portions 55 and the top portions 53 together with the end portion 49 of the extension 47 serve to detachably connect the body portion 39 with the plate member 13'.

80 A comb 19' has the top portion 20' thereof provided with an elongated recess or groove 57 extending from end to end of the top portion 20' for receiving the end 59 of the comb-retaining portion 45 for detachably connecting the comb with the comb-retaining portion.

85 This form of the invention functions in a similar manner to that heretofore described in connection with the form of the invention shown in Figure 1, in that the head of the clipper is moved downwardly with respect to the comb, when pressure is exerted on the clipper by the operator for varying the depth of cut, due to the resiliency of the extension 43.

90 In both forms of my invention it will be noted that body portions and the comb retaining means are disposed over and in spaced relationship with respect to the plate of the clipper, so that the cut hair cannot clog the clipper and prevent the 105 operation thereof.

95 While I have illustrated and described the preferred embodiment of my invention, it will, of course, be understood that various modifications and changes may be made without departing 110 from the spirit or scope of the invention.

I claim:

1. An attachment for hair clippers comprising a comb retaining means, a fastening member pivotally connected with the comb retaining means for connecting the same with a clipper, and a comb connected with the comb retaining means and movable with respect thereto, said fastening member being provided with a comb engaging portion for yieldingly retaining the 120 comb in a given position.

2. An attachment for hair clippers having a clipper plate comprising a comb holder adapted to extend transversely of the clipper plate and having means for attachment to said plate comprising forwardly extending arms provided with recesses for engaging the forward corners of said plate, said arms each having a guide channel therein in a plane intersecting the plane of said plate forwardly of the forward end thereof, a 125 comb slidably disposed in said channels, and a resilient member carried by said holder and engaging said comb for urging the same forwardly within said channels.

3. An attachment for hair clippers having a clipper plate comprising a comb holder having recessed portions into which the forward corners of said plate are adapted to be inserted, means cooperating with said portions for detachably securing said holder in position on said plate and a member carried by said holder comprising a forwardly extending resilient comb engaging arm for yieldingly holding a comb in a plane intersecting the plane of said plate forwardly of the forward edge thereof.

135 GIORGI ADELMO.
